GARMENT HANGER

Bruno J. Hudash, Chicago, Ill.

Application April 10, 1942, Serial No. 438,463

2 Claims. (Cl. 211—34)

This invention relates to improvements in garment hangers and more particularly to a hanger that may be used also as a display rack for displaying goods in stores, shop windows and the like.

A further object is to provide a garment hanger that may be secured to a wall or like support by nails or other fastening means, or that may stand upon a table, show case, display window ledge or the like without fastening means to display goods offered for sale, samples for the trade etc. etc.

A still further object is to provide a garment hanger of light weight, of neat appearance, designed to occupy small space and that is adapted to support or display articles of different types.

A still further object is to provide a garment hanger that is durable in use, inexpensive to manufacture, of few parts and that is designed to carry garments most generally used enabling the wearer to keep them together in a definite place instantly accessible for use.

With the foregoing and other objects in view the invention consists in the combination and arrangement of parts to be hereinafter fully described, pointed out in the claims and illustrated in the accompanying drawing which forms a part of this patent, and in which—

Fig. 1 is a view of the garment hanger in elevational perspective.

Fig. 2 is an enlarged view of Fig. 1 in front elevation with certain adjustable parts in altered positions.

Fig. 3 is a view of the garment hanger in rear elevation, with the adjustable parts in a further altered position.

Fig. 4 is a view of the garment hanger in side elevation illustrating its application.

Fig. 5 is a view in elevation of a modified form of swinging arm that may be employed, and,

Fig. 6 is a detail sectional view of a shoe tree employed.

Like reference characters denote corresponding parts throughout the several views.

The present invention includes a frame having side members 1, 2 which may be formed of flat metal bars or the like, said bars being spaced apart and preferably parallel and offset forwardly as at 3 near their upper ends at an angle of approximately forty-five degrees for a very short distance and then continued vertically, the top-most end portions 4 being bent forwardly at right angles to the main bar portion. Connecting said top end portions 4 at right angles thereto are the oppositely disposed ends 5, 5 of the hat support 55

6, the body portion thereof being preferably of semi-circular shape opening upwardly to receive the crown of a hat 7 as shown in Fig. 4, said hat support being disposed forwardly of said side members 1, 2.

The said side members at their lowermost ends are twisted slightly as at 8 and then extended forwardly to form the base ends 9, 9 connected by the base side 10 thus forming the complete base which is disposed wholly forwardly of said side members, said base extending forwardly beyond the plane of the hat support. Pivoted to the ends 5, 5 of the hat support are the angular wire adjustable supports 11 having heads 12. The pivotal supports 11 are more particularly adapted as supports for ladies' hats although capable of use for other purposes. When not in use said supports 11 may be moved inwardly as shown in Fig. 3 in an out of the way position but when adapted for use may be disposed selectively in altered positions certain of which are shown in Figs. 1 and 2.

Connecting said side members preferably below their portions 3 is a brace and support bar 13 to which a plurality of shoe trees are secured, each comprising a curved arm 14, extending forwardly from said bar, and a toe 15 shaped and adapted to receive and support a shoe 16 in well known manner.

30 The shoe trees and hat support 6 are disposed upon a common side of said side members 1, 2 forwardly thereof and over and above the base 9, 10 so that the weight of garments carried thereby will be disposed over said base and not opposite thereto, to prevent tipping or over-balancing of the hanger. The garments ordinarily carried by the adjustable supports are of such weight that should these supports be moved to dispose their load-receiving heads upon the opposite sides 35 of said side members, with respect to said base, or in the plane thereof they would not over-balance the hanger. An adjustable support arm 17, Fig. 5, having a bent wire head 18 may be substituted for the support 11 when desired, the offset free end thereof being pivotally received in the hat support ends 5, 5.

The support bar 13 is formed with spaced perforations 19 to receive nails to permit the hanger to be secured to a wall when it is not desired to dispose it freely upon its base. The novel features and the operations of this device will be apparent from the foregoing description. While the device has been shown and the structure described in detail, it is obvious that this is not to be considered limited to the exact form disclosed

and that changes may be made therein within the scope of what is claimed without departing from the spirit of the invention.

What is claimed is:

1. In a garment supporter, a frame having side members terminating in forwardly extending top-most ends, an U-shaped hat support adapted to engage the crown of a hat connecting said ends and disposed forwardly of said side members, a base disposed forwardly of said side members, 10

and adjustable hat supports carried by said U-shaped hat support.

2. In a garment supporter, a frame having side members terminating in forwardly extending top-most ends, an U-shaped hat support adapted to engage the crown of a hat connecting said ends and disposed forwardly of said side members, a bar connecting said side members, and a base for said frame disposed forwardly thereof.
